DOOR CLOSER CASING

Samuel F. Rolph, Arlington Heights, Ill., assignor
to The Yale & Towne Manufacturing Company,
Stamford, Conn., a corporation of Connecticut

Application July 1, 1948, Serial No. 147,319

Term of patent 14 years

(Cl. D10—7)

To all whom it may concern:

Be it known that I, Samuel F. Rolph, a citizen of the United States and residing at Arlington Heights, in the county of Cook and State of Illinois, have invented a new, original, and ornamental Design for a Door Closer Casing, of which the following is a specification, reference being had to the accompanying drawings, forming part thereof.

In the drawings, Fig. 1 is a front elevation of a door closer casing embodying my new design. Fig. 2 is an end elevation of the casing. Fig. 3 is a view looking downwardly on the casing. Fig. 4

is a rear elevation of the casing, while Fig. 5 is a view looking upwardly at the casing.

I claim:

The ornamental design for a door closer casing, as shown.

SAMUEL F. ROLPH.
